PNEUMATIC HAMMER

William H. Peck, Royal Oak, Mich.

Application August 25, 1949, Serial No. 112,300

2 Claims. (Cl. 279—19)

1

This invention relates to a pneumatic hammer and more particularly to a pneumatic hammer of the type used in drilling, cutting or riveting. The hammer is operated by compressed air or other pressure fluids in which a reciprocating piston strikes a tool. The tools are removable for replacement purposes and require positive locking means for retaining the tool within the hammer barrel and yet a locking means which is easily assembled and disassembled for quick adjustment or replacement.

It is an object of the present invention to provide a tool retaining means which permits replacement of the tool from the outer end of the hammer barrel and provides positive locking engagement during operation.

Another object of the invention is to provide a reciprocating plunger with means for imparting a rotary motion to the tool during its operation and to provide a tool holding means which will permit free rotation of the tool without disengagement of the holding means.

Other objects and advantages of the invention will more fully appear from the following description taken in connection with the accompanying drawings in which:

Fig. 1 is a side elevational view of a pneumatic hammer embodying one form of the invention;

Fig. 2 is an enlarged sectional view of a portion of the hammer showing the rotating means and holding means for the tool;

Fig. 3 is a sectional view taken on line 3—3 of Fig. 2;

Fig. 4 is a sectional view taken on line 4—4 of Fig. 2; and

Fig. 5 is a perspective view of the reciprocating member.

Referring to the drawings, I have shown a pneumatic hammer 10, having a barrel 12 and a handle 14. The handle is provided with a connection 16 for communication with an air pressure line 18 connected to a source of pressure, not shown. A control is shown at 20 for admitting the air pressure to the operating parts of the hammer which are of conventional construction.

A tool 22 is removably received in the barrel end of the hammer and is securely held in operating position by a locking mechanism which will permit axial movement of the tool, relative to the hammer barrel, and rotary movement therewith.

In pneumatic hammers of the type selected for illustrating the invention, the hammer 10 is provided with a reciprocating piston 24 which contacts the inner end of the tool 22 for transmitting

2

the percussive forces to the tool. The piston 24 is supported in a bushing 26 at the outer end of the hammer. The cylindrical barrel 12 is secured to the end of the hammer 10 by bolts 28 extending through laterally disposed ears 30 on the barrel 12 and handle 14. The bushing 26 is provided with an outer flange 32 which is positioned between the adjacent ends of barrel 12 and hammer end 10.

10 The outer periphery of the piston 24 is provided with spiral splines 34, Fig. 5, which receive a ratchet wheel 36. An internally splined bushing 38, in axial alignment with the bushing 26, is journaled in the barrel 12 and the ratchet wheel 36 is positioned between the adjacent thrust faces of the bushings 26 and 38. The splined bushing 38 fits the splines 34 of the piston 24 and receives rotary motion by the reciprocating movement of the piston 24.

20 Referring to Fig. 3, I have shown the ratchet wheel 36 in co-operation with dogs 40 which are pivotally supported in the housing of the barrel 12 and are urged toward the ratchet wheel 36 by springs 42. As is common in designs of this type, 25 the dogs 40 permit rotation of the ratchet wheel in one direction only when the piston 24 is moved in one axial direction. When the piston 24 is moved axially in the opposite direction, the ratchet wheel is held against rotation by the dogs 40 and the piston is rotated.

25 A sleeve 44 fits the outer periphery of the tool shank 46 and is rotatably supported in the outer end of the barrel 12. The inner end of the sleeve 44 projects beyond the inner end of tool shank 46 and is provided with notches 48 in its inner end which fit correspondingly shaped projections 50 on the bushing 38, similar to a jaw clutch construction, so that rotation of the bushing 38 causes rotation of the sleeve 44.

30 It is desirable to have the tool rotate during upward movement of the piston 24 and to be non-rotatable during downward movement or on the percussion stroke. Therefore, the ratchet wheel 36 is free to rotate in a counter clockwise direction when the piston is moving upwardly into the hammer. The spiral splines 34, in co-operation with the splines of the ratchet wheel, cause rotation of the ratchet wheel 36 and rotation of the bushing 38 imparting rotary movement to the sleeve 44. During outward movement of the piston 24, the ratchet wheel 36 is held against rotation by the dogs 40 and the splines rotate the piston 24 without imparting rotary movement to the bushing 38, sleeve 44 or tool shank 46.

35 When the barrel 12 is attached to the outer end

of the hammer 10 by the bolts 28, with the bushing 26 between the adjacent ends of the barrel and hammer, the ratchet wheel 36, bushing 38 and sleeve 44 may be inserted through the outer end of the barrel 12 with the wheel 36 and bushing 38 on the splines 34 of the piston 24. The sleeve 44 is held in the barrel 12 by a removable coil spring member 52 which fits co-operating grooves 54 and 56 in the adjacent surfaces of the sleeve 44 and barrel 12, respectively. An opening 58 through the wall of the barrel 12 co-operates with the grooves for inserting the spring 52 into the grooves 54 and 56.

Ball receiving apertures 60 are formed in the wall of the sleeve 44 for the reception of balls 62 having a diameter greater than the wall thickness of the sleeve 44.

A retainer sleeve 64 surrounds the sleeve 44 and balls 62 and is axially slidable on the outer end of the sleeve 44. The sleeve 64 is retained on the sleeve 44 by a split ring retainer 66 which fits a groove in the outer end of the sleeve 44. A compression spring 68 between a shoulder 70 on the sleeve 44 and a shoulder 72 on the sleeve 64 urges the sleeve 64 outwardly against the ring 66. In this position the shoulder 72 bears against the outer periphery of the balls 62 holding the latter in axially extending grooves 74 formed in the tool shank 46. Between the shoulder 72 and the outer end of the sleeve 64 is an annular recess 76 which, when the sleeve 64 is moved inwardly against the compression of the spring 68, the balls are free to move radially outwardly into the recess 76, permitting removal of the tool. The grooves 74 permit the relative axial movement of the tool and sleeve during operation.

The sleeve 64 is further provided with an inwardly extending portion 78 which normally fits over the barrel 12 and covers the opening 58 so that there is no danger of the spring 52 leaving the grooves 54 and 56, thereby locking the sleeve 44 to the barrel and at the same time permitting relative rotation there between.

If it is desired to replace the tool, the sleeve 64 is slid inwardly and the tool removed. If it is desired to remove the sleeve 44, bushings 38 and 26 and the ratchet wheel 36 the split ring 66 is removed and then the spring 52. This permits sliding the parts outwardly through the barrel 12.

While I have illustrated and described a preferred embodiment of the invention, it will be understood that various changes including the size, shape and arrangement of parts may be made without departing from the spirit of my invention and it is not my intention to limit its scope other than by the terms of the appended claims.

I claim:

1. A releasable holding means for a shanked tool at the end of the barrel of a pneumatic hammer comprising, a sleeve fitted into the open end of the hammer barrel and to slidably receive the shank of a tool therein, said tool shank having circumferentially spaced and axially extending grooves in its outer periphery, said sleeve having ball apertures through the wall thereof

radially opposed to the grooves in said tool shank, balls in the apertures having a diameter greater than the thickness of the wall of said sleeve, a second sleeve surrounding said first named sleeve and having axial movement relative to said sleeve, said second named sleeve having a portion of its inner periphery substantially equal to the outer diameter of said first named sleeve for maintaining the outer surface of said balls substantially at the outer periphery of said first named sleeve when in one of its axial positions on said first named sleeve and having a recess for receiving said balls so that said balls may be positioned outwardly beyond the outer periphery of said tool shank when said last named sleeve is in another of its axial positions on said first named sleeve, and a locking means between said first named sleeve and said barrel which will permit rotation of said first named sleeve relative to said barrel but retain the same against relative axial movement.

2. A releasable holding means for a shanked tool at the end of the barrel of a pneumatic hammer comprising, a sleeve fitted into the open end of the hammer barrel and adapted to slidably receive the shank of the tool therein, said tool shank having circumferentially spaced and axially extending grooves in its outer periphery, said sleeve having ball apertures through the wall thereof radially opposed to the grooves in said tool shank, balls in the apertures having a diameter greater than the thickness of the wall of said sleeve, a second sleeve surrounding said first named sleeve and having axial movement relative to said first sleeve, said second sleeve having a portion of its inner periphery substantially equal to the outer diameter of said first named sleeve for maintaining the outer surface of said balls substantially at the outer periphery of said first named sleeve when in one of its axial positions on said first named sleeve and having a recess for receiving said balls so that said balls may be positioned outwardly beyond the outer periphery of said tool shank when said second sleeve is in another of its axial positions on said first named sleeve, a locking means between said first named sleeve and said barrel which will permit rotation of said first named sleeve relative to said barrel but retain the same against relative axial movement, and a portion on said second sleeve projecting over said locking means when said second sleeve is in either of the aforesaid axial positions.
